FAUCET AND DIAL VALVE CONTROL COMBINATION

Fred C. Alexander, New Castle, Pa., assignor to Universal Rundle Corporation, New Castle, Pa., a corporation of Delaware

Application December 10, 1956, Serial No. 44,135

Term of patent 14 years

(Cl. D91—3)

FIG. 1

FIG. 2

Fig. 1 is a perspective view of a faucet and dial valve control combination embodying my new design; and

Fig. 2 is a side elevational view of the same.

The side not shown is substantially like the side illustrated in the drawings.

I claim:

The ornamental design for a faucet and dial valve control combination, as shown and described.
